EDWARD KIRBY BOTTLE, OF ELMIRA, NEW YORK, ASSIGNOR TO AMERICAN SALES BOOK COMPANY, LIMITED, OF TORONTO, ONTARIO, CANADA, A CORPORATION OF ONTARIO, CANADA

MANIFOLDING SALES BOOK

Application filed September 14, 1921. Serial No. 500,496.

This invention relates to manifolding devices and with respect to its more specific features to manifolding books such as sales books and the like.

5 One of the objects of the invention is the provision of a manifolding book of simple construction capable of being efficiently utilized to make four copies at one writing.

Another object of the invention is the 10 provision of a simple and efficient construction for manifolding books wherewith the same may include standard parts capable of being readily assembled to provide a complete book for making three copies at one 15 writing or a complete book for making four copies at one writing.

Other objects will be in part obvious and in part pointed out hereinafter.

The invention accordingly consists in the 20 features of construction, combinations of elements and arrangement of parts which will be exemplified in the construction herein-after set forth, and the scope of the application of which will be indicated in the following claims.

In the accompanying drawings forming part of this specification wherein similar reference characters refer to similar parts throughout the several views,

30 Figure 1 is a perspective view of a manifolding sales book embodying the invention;

Fig. 2 is a perspective view illustrating the manner of associating the record leaves and transfer leaves of Fig. 1, for manifolding;

Fig. 3 is a detail showing the manner of attaching the transfer sheets;

Fig. 4 is a diagrammatic view in perspective showing a manner of associating a single transfer sheet with a set of record leaves which may be employed;

Fig. 5 is a diagrammatic view in perspective showing the manner of utilizing a folded transfer sheet with three record leaves which may be employed;

Fig. 6 is a diagrammatic view in perspective showing the leaves of the main sets of record leaves attached together in a somewhat different manner from that of Fig. 1;

50 Fig. 7 is a detail view illustrating a man-

ner of removably attaching one of the sets of record leaves to the support;

Fig. 8 shows a different arrangement for the main sets of leaves; and

Fig. 9 shows a further modification of 55 Fig. 1.

Referring now more specifically to the drawings, the numeral 1 indicates a support which may be made of stiff material as heavy paste-board, and the numeral 2 indicates a 60 similarly stiff back hinged to the support 1 at 3 and adapted to lie in superposed relation to the latter. In practice, the backing and support may be covered with cloth to give a finished appearance and provide 65 against wear, and the hinge between the two may be formed by a connecting part of such cloth. At 4 is indicated a cover which may be connected to the support 1 by the cloth referred to so as to form the flexible part 5 70 which enables the cover to be turned into position overlying the support 1.

Removably fastened to the back 2 are a plurality of sets of record leaves forming a main pad indicated generally by the numeral 6.

For fastening the main pad 6 to the back 2 a spring clamp carried by the back may be provided, this clamp gripping the stub of the pad and holding it firmly on the back so as to move therewith on the hinge 3. The 80 pad 6 is composed of a plurality of main sets of record leaves, each set including three record leaves, in superposed relation as shown in Fig. 1, where the three record leaves of one set referred to, are indicated by the numerals 8, 9 and 10.

One of these three leaves, as the leaf 9, is somewhat longer than the other two to provide a stub portion 11, and the stub portions of the leaves of each main set are bound together as by the staples 12.

The second and third leaves of each set are connected to the bound leaves and are thereby held in the pad, and consequently in the book, by the bound leaves. In the embodiment illustrated in Fig. 1 the original leaf 8 on which the inscription is made and the duplicate leaf 9 are included in a folded sheet, the leaves 8 and 9 being integrally connected together along the line 13 which is transverse to the axis of the hinge 3, the 95

100

sheet being weakened at the fold 13 to facilitate tearing the leaves 8 and 9 apart. Also in the embodiment illustrated in Fig. 1, the third leaf 10 is intermediate the original and duplicate leaves 8 and 9 and is pasted to the upper face of the under, or duplicate, leaf adjacent the fold 13, the numeral 14 indicating a portion of the pasted area. Thus it will be seen that the three record leaves 8, 9 and 10 are connected to each other and may be readily torn, as one, from the pad along the weakened line 15 in the duplicate leaf. While the intermediate, triplicate leaf 10, may be made of opaque material similar to the material of the leaves 8 and 9, the triplicate leaf is usually made of translucent material so that inscription on one face may be read through the thickness of the leaf. At 16 is indicated a supplemental set of record leaves which are adapted to be superposed in manifolding relation with the leaves of the main sets. The leaves 16 may be of tissue and provided by a thin supplemental, or second, pad of tissue leaves, which is removably attached to the support 1 alongside the main pad and on the side of the latter opposite the hinge 3. With this disposition of the supplemental pad it will be seen that the leaves 16 thereof work from a position at the side of the main sets, opposite the hinge 3 and at an angle to the line of connection between the original and triplicate leaves 8 and 10, the leaves 16 being movable sidewise of the main pad into and out of superposed relation relative to the latter.

It is to be understood that any suitable disposition of transfer material may be employed for transferring impressions from the original to the other record leaves in superposed relation. In the embodiment illustrated in Fig. 1 two transfer leaves are indicated at 17 and 18, these leaves being carbon transfer leaves coated on both faces. The transfer leaves work from a position at the side of the main set of record leaves into manifolding relation with the latter as illustrated in Fig. 1, and it will also be observed that in the same figure the transfer leaves work from the same side as do the leaves 16 of the supplemental pad. The transfer leaves 16 may be operatively attached to move with the main pad on its hinge 3 and to this end they may be stitched at one side to a sheet of relatively heavy manila paper 19, Fig. 3, which may be bound in place by the staples 12 so as to form a part of the main pad. The sheet of manila 19 underlies the record leaves of the main pad so that the transfer leaves come into operative manifolding position by extending between the main pad and the supplemental pad in the form illustrated, Fig. 1.

The operation of the embodiment illustrated in Fig. 1 will now be understood. The original and triplicate leaves 8 and 10 are lifted and the transfer sheet 17 laid upon

the duplicate leaf 9. Thereupon the triplicate leaf 10 is placed against the upper face of the transfer sheet 17 and the transfer sheet 18 is laid upon the upper face of the triplicate leaf. Then one of the supplemental leaves 16 is moved into position on the upper face of the transfer leaf 18, whereupon the original leaf 8 is permitted to fall upon the upper face of the supplemental leaf 16. The arrangement will be clear from Fig. 2. An inscription upon the original leaf 8 will then be duplicated upon the leaves 9, 10 and 16. After inscription, the folded end of the original and duplicate leaves may be grasped and these leaves torn from the pad along the weakened line 15. Thereupon, or even before removing the main set, the main pad and the back 2 may be rotated on the hinge 3 so as to permit the leaf 16 to drop on to the upper face of the support 1, in which position it will be held out of the way and kept flat by the return of the back 2 into superposed relation on the support 1. Thereupon the book is ready to be set for a second inscription.

In Fig. 5 the numeral 20 indicates a transfer sheet which may be held to the pad as are the two transfer sheets depicted in Fig. 2, so as to work from a position at the side of the main sets. The sheet 20 has an extended portion 21 which is integral with the attached part 20 and is adapted to be reversely folded into superposed relation with the record leaves. The operation of a sales book equipped with the modification of Fig. 4 is substantially similar to that explained in connection with Fig. 1 except it will be observed that the transfer extension 21 takes the place of the transfer sheet 18 of the latter figure.

If only three records of the inscription are sought, the transfer leaf 17 or the transfer sheet 20 may be utilized in connection with the main sets of record leaves in a manner which will be clearly understood from the foregoing. It is observed in this connection, however, that the supplemental pad 16 and the transfer sheet 18, as well as the extension 21, will not interfere with the operation of the book as a triplicating book. Thus the present invention, in addition to providing for as many as four records of the original writing, also provides a book in which standard parts, such as the pad 16 and the transfer leaf 18, may or may not be employed, dependent upon the ultimate result sought.

In the modification illustrated in Fig. 4 is shown a single transfer sheet 22 which may be employed in connection with the record leaves of the main pad for obtaining records in triplicate as just explained. Of course, it is to be understood that the single transfer sheet 22 may be attached to the pad as are the leaves 17 and 18 of Fig. 1.

Instead of pasting the triplicate leaf 10 to the upper face of the duplicate leaf 9 as il-

lustrated in Fig. 1, it may be pasted to the under, or lower face of the original leaf 8 as indicated in Fig. 6. In this figure the numeral 23 indicates the triplicate leaf which 5 may be translucent or opaque and is pasted to the leaf 8 adjacent the fold, as indicated at 24. Or the triplicate leaf may be pasted to the duplicate leaf near the stub end of the duplicate as indicated in Fig. 8, where the 10 original and duplicate integrally connected leaves are indicated by the numerals 34 and 25, the intermediate leaf 26 being pasted to the upper face of the duplicate along the shaded area 27.

15 In the modification illustrated in Fig. 9 the construction is similar to that illustrated in Fig. 1, except that in the former figure the transfer sheets work from the side of the book opposite the supplemental pad, and the 20 intermediate or triplicate leaf is attached, as by being pasted, to the top, or outer, end of the original leaf 8. In Fig. 9 the supplemental pad of tissue leaves is seen at 16 working from the left hand side, as in Fig. 1. The 25 two transfer sheets are indicated by the numerals 30 and 31, these sheets coming from the right hand side and being held to the pad of main record leaves in a manner similar to that hereinbefore explained in connection 30 with Fig. 1. In Fig. 9, however, the setting of the book for inscription is as follows: The lower transfer sheet or leaf 31 is disposed on the upper face of the original record leaf 9; thereupon one of the tissue leaves 16 is placed 35 upon the transfer sheet 31 and then the upper transfer sheet 30 is placed on the inserted tissue leaf. Then the triplicate, or intermediate, record leaf 32, together with the original leaf 8 to which it is pasted along the area indicated at 33, is placed upon the upper face 40 of the transfer sheet 30.

Instead of having the two transfer sheets work from the same side, one might be attached to the stub of the main set so as to 45 work from the top end of the book, the other working from the side.

Thus by the above described construction are accomplished among others the objects hereinbefore referred to.

50 As many changes could be made in the above construction and many apparently widely different embodiments of this invention could be made without departing from the scope thereof, it is intended that all matter contained in the above description or 55 shown in the accompanying drawings shall be interpreted as illustrative and not in a limiting sense.

Having described my invention, what I 60 claim as new and desire to secure by Letters Patent is:—

65 1. A manifolding book including, in combination, a plurality of main sets of record leaves, a supplemental set the record leaves of which are adapted to be placed in mani-

folding relation with those of the main set, and transfer material adapted to transfer inscription from one to another of superposed record leaves, each main set including three record leaves, in manifolding relation, 70 one of which leaves is bound to the book and the second and third of which are connected to the first to be held in the book thereby, two of said three leaves being included in a folded sheet, the other leaf being pasted to the latter adjacent the fold, the leaves of said supplemental set working from a position at the side of said main sets, at an angle to the line of connection of said other leaf, said transfer material including two transfer 75 leaves working from a position at the same side as the supplemental leaves.

2. In a manifolding book, in combination, a main pad having record leaves arranged in a plurality of main sets and mounted so as to swing in one direction, a supplemental set of record leaves mounted to swing at an angle to the plane of swinging movement of the leaves of the main sets and to move thus into manifolding relation with the latter sets, and 85 a transfer sheet mounted to swing substantially in the plane of the swinging movement of the leaves of said supplemental set and working from a position at the side of said main sets so as to be moved into over-lapping 90 manifolding relation with the leaves of said main sets upon said pad.

3. In a manifolding book, in combination, a main pad having record leaves arranged in a plurality of main sets and mounted so as to swing in one direction, a supplemental set of record leaves mounted to swing at an angle to the plane of swinging movement of the leaves of the main sets and to move thus into manifolding relation with the latter sets, and 100 a transfer sheet mounted to swing substantially in the plane of the swinging movement of the leaves of said supplemental set and working from a position at the side of said main sets so as to be moved into overlapping 105 manifolding relation with the leaves of said main sets upon said pad, both the supplemental set of record leaves and the transfer sheet being positioned at the same side of the 110 main pad.

4. In a manifolding book, in combination, a main pad having record leaves arranged in a plurality of main sets and mounted so as to swing in one direction, a supplemental set of record leaves mounted to swing at an 115 angle to the plane of the swinging movement of the leaves of the main sets and to move thus into manifolding relation with the latter sets, and a transfer sheet mounted to swing substantially in the plane of swinging movement of the leaves of said supplemental set and working from a position at the side of said main sets so as to be moved into overlapping 120 manifolding relation with the leaves of said main sets upon said pad, a supporting 125 sheet being positioned at the same side of the main pad.

back for said main pad mounted so as to swing with the pad to permit the leaves of the supplemental set to be swung into storage position beneath said supporting back, and said transfer sheet being carried for swinging movement with said supporting back.

5. In a manifolding book, in combination, a main pad having record leaves arranged in a plurality of main sets and mounted so as to swing in one direction, a supplemental set of record leaves mounted to swing at an angle to the plane of swinging movement of the leaves of the main sets and to move thus into manifolding relation with the latter sets, and a transfer sheet mounted to swing substantially in the plane of the swinging movement of the leaves of said supplemental set and working from a position at the side of said main sets so as to be moved into overlapping manifolding relation with the leaves of said main sets upon said pad, a supporting back for said main pad mounted so as to swing with the pad to permit the leaves of the supplemental set to be swung into storage position beneath said supporting back, and said transfer sheet being carried for swinging movement with said supporting back, both the supplemental set of record leaves and the transfer sheet being positioned at the same side of the main pad.

In testimony whereof I affix my signature.
EDWARD KIRBY BOTTLE.
